UNITED STATES PATENT OFFICE.

MARSHALL D. WELLMAN, OF PITTSBURG, PENNSYLVANIA.

IMPROVEMENT IN FIRE-PLACE STOVES.

Specification forming part of Letters Patent No. 42,312, dated April 12, 1864.

To all whom it may concern:

Be it known that I, MARSHALL D. WELLMAN, of the city of Pittsburgh, in the county of Allegheny and State of Pennsylvania, have invented a new and useful Improvement in Open Fire-Places; and I do hereby declare the following to be a full, clear, and exact description thereof, reference being had to the annexed drawings, forming part of this specification, in which—

Figure 1 is a front view of an open fire-place constructed with my improvements. Fig. 2 is a vertical section through the center of the fire-place at *x x*, Fig. 1. Fig. 3 is a rear view of my improved fire-place. Fig. 4 is a top view of my fire-place. Fig. 5 is a horizontal section through the fire-basket at *v v*, Figs. 1 and 2. Fig. 6 is a horizontal section below the grate-bars through *z z*, Figs. 1 and 2.

In the several figures like letters of reference denote similar parts.

My improvements are designed to accomplish the following important results, viz: first, to give a more perfect control over the combustion of the fuel, so that the fire may be made to burn up and give out a great degree of heat, or be caused to burn slowly while still emitting considerable heat, as may be desired; second, to effect a saving of fuel by regulating its consumption and more perfectly utilizing the heat emitted therefrom, and by causing a larger proportion of heated air to pass into the apartment to be warmed; third, to secure a more perfect ignition and consumption of the fuliginous and gaseous products of the coal; fourth, to prevent the soot and fine ashes from passing from the chimney and fire-place into the room.

To enable others skilled in the art to make use of my improvements, I will proceed to describe the construction and operation of an open fire-place on my improved plan.

Fig. 1 is a front elevation of a parlor fire-place, consisting chiefly of a front piece or arch, a fire-wall and fire-basket, ash-pan, smoke-flues and dust-pipes, and screen for preventing soot or dust from falling into the smoke-flues, all of which parts are connected together, and are designed to be set into the wall between the jambs or side walls, and immediately under the throat of the chimney.

The front piece or arch, *a*, of the fire-place may be made of cast-iron in one piece, and

with it are connected meditately or immediately all the other parts of the fire-place. When the fire-place is set in the chimney, the front piece, *a*, is set out a short distance from the front wall of the chimney, so as to leave a space on both sides and on top for the circulation of air around the flues and back wall, which will thus become heated, and thence (having no access to the chimney) will pass into the room. The space around the arch and between it and the wall of the chimney may be covered with ornamental perforated iron-work, or openings may be made in the front piece near the bottom for the entrance of cold air, and at the top for the exit of heated air, in which case the edge of the front piece may be set close up to the wall.

The fire-wall *b* of the fire-place may be made either of cast-iron or fire-clay tile, and extends from the bottom plate, *d*, of the fire-place to the horizontal top plate or covering, *j*. The bottom plate, *d*, and top plate, *j*, surround the flues and pipes and fire-wall, and extend around them backward and on either side to the walls of the chimney, and thus inclose a space back of the fire-wall, through which the air circulates from and into the apartment, as before stated, the top plate preventing the passage of air up the chimney otherwise than through the flues and dust-pipes. The bottom plate, *d*, is situated at the level of the top of the ash-pan *e*, and the top plate being situated near the top of the arch or front piece, *a*. The lower part of the fire-wall *b* rests on the bottom plate, *d*, and is fastened by bolts or otherwise to the front piece, *a*.

c is the grate or fire-basket, the horizontal bars of which, forming the fire bed, extend backward into the fire-wall *b*, as seen in Fig. 2. The fire-wall *b* may be shaped, as shown in Figs. 4, 5, and 6, so that its horizontal section will be semicircular, or it may be semi-elliptical or have three plane sides. Whatever may be its shape, the back part of the wall, fronting the opening of the fire-place, slopes or inclines forward and upward from the level of the grate-bars of the fire-basket at an angle of about forty-five degrees toward the top plate, *j*, of the fire-place. This peculiar conformation of the back part of the fire-wall is an important feature of my improvement, and has the effect of allowing the air to pass up along the surface of the sloping wall back of

the fire, and of deflecting the air upon the fire, and thus burning the unconsumed smoke and gas. It also prevents the fuel before it is coked from packing against the back wall and obstructing the passage of air, because coal when thrown together loosely in a heap will assume naturally an angle of about forty-five degree to the horizon, and this angle, whatever it may be, which the fuel naturally assumes, is the angle at which I propose to set the back part of my fire-wall. It may be varied in different fire-places to suit the peculiar description of coal to be burned but I find the angle of forty-five degrees to suit with bituminous coal.

Between the top of the fire-wall *b* and the front piece, *a*, is an opening, *g*, (which is shown by dotted lines in Fig. 4,) through which the smoke and flame from the fire pass into the short horizontal flue *f* on top of the top plate, *j*, so that the smoke escaping from the flue *f* passes up the chimney. The mouth of the short flue *f* is closed (when the fire-place is not in use) by a slide, *i*, which has a horizontal plate, *k*, attached to it resting on the top plate, *j*. The plate *k* has an orifice, *l*, corresponding with the mouth of the vertical flue *m*, which orifice is so situate that when the slide *i* is pushed back by the rod *n* so as to open the horizontal flue *f*, the mouth of the vertical flue *m* is also open; but when the flue *f* is closed, by drawing forward the rod *n*, the plate *k* slides forward and closes the vertical flue *m*. In the rear of the fire-wall *b* is placed a vertical flue, *m*, which opens at *l* (see Fig. 2) through the top plate, *k*, and extends down below the level of the grate-bars, where it opens into the space below the grate and above the ash-pan *e*. The lower end of the flue *m* is always open, and through it passes an upward current of air (when its mouth at *l* is open) from under the fire-basket, carrying with it any fine ashes which fall from the fire-grate, and which might otherwise pass outward into the room. The dust thus borne by the draft into the air-flue *m* will either be carried upward through the top plate, *j*, and fall down the dust-pipe *p* into the ash-drawer *e*, or will drop down again through the vertical flue *m*, and thus also pass into the ash-drawer *e*, so that the air-flue *m* cannot possibly become choked.

In the bottom plate, *d*, above the ash-drawer *e*, is a grating, *q*, (see Figs. 5 and 6,) which also extends under the air-flue *m*, the grating *q* allowing the ashes and fine cinders from the fire and from the air flue *m* to fall into the ash-drawer *e*, which lies under the bottom plate, *d*, and extends under the flue *m* and dust-pipes *p*, as well as under the fire-basket. On either side of the air flue *m* is a vertical dust-pipe, *p*. These two dust-pipes *p* extend from the top plate, *j*, to the bottom plate, *d*, (see Figs. 2 and 3,) opening through the top plate, *j*, into the chimney and through the bottom plate, *d*, into the dust-drawer *e*. The openings in the bottom plate, *d*, at the bottom of the dust-pipes *p* are furnished with slides *r*,

which may be opened or closed at pleasure by rods *s s*, extending to the front of the fire-place on either side, and which will be concealed by a fender.

Above the top covering plate, *j*, in the chimney is placed a lattice-screen composed of strips of sheet-iron *t*, each of which inclines downward in width, and is placed horizontally across the chimney in length. They are parallel to each other, and one above another, but do not touch. These strips are placed in two series, which meet at the top, rising from the inner edge of the openings at the top of the dust-pipes to a point vertically over the air flue *m*. As these strips *t t* all incline downward from the apex on either side, and each one in the descending series extends a little farther from the center than the strip above it, the smoke can pass up freely between the strips into the chimney; but no solid substance—soot, dust, or ashes—can find their way downward between the strips, but will fall over them, as down an inclined plane, to one side or the other, into the dust-pipes *p p*, and thence into the ash-drawer *e*, because the top plate, *j*, entirely closes the chimney, so as to prevent the passage of air upward from below the plate, or of soot or dust downward from above it, excepting through the flues *f* and *m* and dust-pipes *p p*, as before explained.

In the fire wall *b* are a number of vertical air-passages, *v v*, which extend upward from the level of the grate-bars to a point about that at which the fuel is to reach in the fire-basket. These air-passages are simply fluted recesses in the fire-wall to allow air to pass upward back of the fuel in the grate. They are made larger at bottom than at top, or tapering upward, so that any cinders or ashes which collect in them will easily drop out or may be removed by a touch from the poker. One such fluted recess *v* occurs just over each space between the grate-bars *c'*, so that the air has free access to these recesses, and the closing of the spaces between the grate-bars *c'*, as hereinafter explained, will also close the air-passages and prevent the access of air to the back part of the fire.

Under the horizontal grate-bars of the fire-basket, and in immediate contact therewith, are a series of bars, *u u*, one under each grate-bar *c'*, forming a sort of double grate. To each of these bars *u* is pivoted a slat or strip of iron, *w*, by which the space between the bars may be closed. These slats are attached to the bars *u u* by a pin projecting from their upper edge at each end, so that they may hang down when the spaces between the bars are opened, and as the bars *u* are thinner than the grate-bars above them, and the slats are also thin, the slats do not, when hanging down, contract the spaces between the bars. On the lower side of each slat, at its front end, is a projecting pin, *x*, which enters a slot in a sliding bar, *y*, (see Fig. 1,) so that when the sliding bar *y* is moved to one side, the slats connected with it by the pins *x* are all simulta-

neously turned on their pivots until the lower edge of each slat comes in contact with the bar u next to it, thus closing the space between the bars and preventing the passage of air through them. The ashes which settle between the grate-bars soon close any interstices through which the air might pass by reason of the slats not fitting closely to the bars. There are two sliding bars, y and y' , to open and close the slats u , placed end to end in front of the fire-place under the grate-bars, and in front of the bars u , to which the slats are pivoted, half of the slats u being operated by one sliding bar, y , and the remainder by the other sliding bar, y' . The sliding bars may be operated simply by pushing them backward and forward with a poker, or by means of ratchet-teeth in the end of the bars engaging the cog-teeth of a pinion, z , worked by a button, o , projecting from the front a of the fire-place.

Instead of pivoting the slats to an under grating placed beneath the grate-bars, as just described, the slats may be pivoted immediately to the grate-bars, or otherwise so attached to the under side of the fire-basket c as to be turned simultaneously to close or open the spaces between the grate-bars at pleasure.

Having thus described the construction of my improvement in fire-places, I will briefly explain its use and mode of operation.

My improved fire-place is peculiarly adapted for burning the more bituminous description of coal, such as cannel-coal and stone-coal, which yield a large amount of smoke, gas, and fine ashes; but it may be used with equal advantage in many respects with anthracite and other coals which are but slightly bituminous.

When a fire is to be freshly built in my fire-place, the buttons o are turned so as to draw the sliding bars y and y' to either side, and thus open the space between the grate-bars in the under side of the fire-basket, and also open the air-passages v in the fire-wall. The rod u is also pushed back, which opens the smoke-flue f and air-flue m . The slides r at the bottom of the dust-pipes p are closed, being opened only when it is desired to clean the dust-pipes of any soot or dust which may have fallen down the chimney, while the spaces between the grate-bars are left open, so as to allow air to pass freely between the bars and up the air-passages v in the fire-wall. The fire in the grate will burn briskly, and the fuel will consume rapidly, giving out a great degree of heat, because the free supply of air, especially to the back of the fire, causes a thorough ignition of the fuel and of the smoke and gas evolved therefrom, and thus produces a large body of flame with little unconsumed smoke or gas. By this arrangement and the sloping of the fire-wall the smoke and gas are almost entirely consumed instead of passing up the chimney, as is the case with fire-places of ordinary construction; and thus a great saving of fuel is effected. When the fuel is fully ignited, the slats may be closed, which excludes the air from the air-passages v , and

prevents its passing up between the grate-bars. The fire will then burn slowly, but will still emit a sufficient heat, the surface of the fuel in the fire-basket remaining red-hot, and burning downward until all is consumed. The fire will remain in this condition, with the slats closed, for a much longer time than in ordinary grates, and will not require stirring or the replenishment of fuel. When fresh fuel is added, the slats may be opened slightly, so as to admit sufficient air to consume the smoke and gas, and then closed again, when the fuel becomes coked. The air-flue m serves to draw up any dust or ashes that fall from the fire-basket, and keeps up a good draft in the chimney without having a large opening to the smoke-flue f , which should be opened so far only as to prevent the fire smoking. The space in the rear of the fire-wall of the fire-place, inclosed above and below by the top plate, j , and bottom plate, d , serves as an air-heater. The cool air, entering from the apartment near to the ground and circulating around the heated back wall, b , and flue m , is warmed, and rising passes out into the room higher up.

It is well known by those who are in the habit of using bituminous coal that large quantities of soot collect in the chimney, which, when the fires are put out in summer, and sometimes even when there is a fire in the grate, falls down the chimney into the room, to the destruction of carpets and other articles of furniture. To avoid this, housekeepers usually stop up the throat of the chimney in summer, thereby preventing the passage of air up the chimney, which is important for ventilation, and rendering it impossible to light a fire without removing the obstruction, which is always attended with a downfall of soot or dirt. My arrangement of dust-pipes and lattice-screen placed over the air-flue and smoke-flue effectually prevents any fall of soot into the room, as all such matters fall on the screen and are thereby conducted to the dust-pipes, whence they may be discharged into the ash-drawer by opening the slides r .

When the fire-place is not in use, the damper k may be drawn forward so as to close the smoke-flue f entirely, when the air-flue m will also be closed; or, if preferred for the purposes of ventilation, the damper k may be drawn forward sufficiently to cover the air-flue m without entirely closing the smoke-flue f .

What I claim as my invention, and desire to secure by Letters Patent, is—

1. The use in the back and side fire-walls of fire-places of flutes extending downward from a point about the ordinary level of the top of the fuel, and gradually increasing in size until they terminate at the level of the grate-bars of the fire-basket, the lower end of each such flute coinciding with an opening between the grate-bars, for the purposes hereinbefore set forth.
2. The use of a series of horizontal strips or

slats placed underneath or between the bars and independent thereof, and so arranged as to turn on their axes, closing or opening at pleasure the air-spaces between the grate-bars.

3. Sloping the back or fire wall forward over the fire from a point at or below the level of the fire-bed, so that the coal or fuel will not be inclined to pack down against the back wall, and thus allowing the upward passage of the air between the back wall and the fire, substantially as hereinbefore described.

4. The combination of the lattice or screen *t* with the air-flue *m* and dust pipe or pipes *p*,

for the purpose of preventing the descent of dust or soot into the fire-grate and collecting them in a separate receptacle, substantially as described.

5. The use of the sliding cap *k*, when so arranged in combination with the air-flue and smoke-flue as to close them simultaneously.

In testimony whereof I, the said MARSHALL D. WELLMAN, have heréunto set my hand.

MARSHALL D. WELLMAN.

In presence of—

JAMES OLD,

W. BAKEWELL.
